Primary Examiner — Darlington Ly

(57) **CLAIM**

The ornamental design for a vehicle tire, as shown and described.

DESCRIPTION

1. Vehicle tire

1.1 is a front perspective view of a vehicle tire embodying my new design;

1.2 is a front elevation view thereof;

1.3 is a rear elevation view thereof;

1.4 is a left side elevation view thereof;

1.5 is a right side elevation view thereof;

1.6 is a top plan view thereof; and

1.7 is a bottom plan view thereof.

The broken lines in the reproductions illustrate portions of the vehicle tire that form no part of the claimed design.

The dash-dot broken lines are provided to represent boundaries of the claimed design.
